(Cl. D81—10)

To all whom it may concern:

Be it known that we, Charles A. Reichelderfer, Herman G. Raymer, and Harold L. Herzog, citizens of the United States, residing at Columbus, in the county of Franklin and State of Ohio, have invented a new, original, and ornamental Design for a Gas-Fired Unit Heater or Similar Article, of which the following is a specification, reference being had to the accompanying drawing, forming a part thereof.

Fig. 1 is a side elevational view of a gas-fired unit heater or similar article, showing our new design;

Fig. 2 is a top plan view; and

Fig. 3 is a bottom plan view thereof.

The grille work, as shown in segments in the drawing, extends completely around the heater.

We claim:

The ornamental design for a gas-fired unit

heater or similar article, substantially as shown and described.

CHARLES A. REICHELDERFER.

HERMAN G. RAYMER.

HAROLD L. HERZIG.
